UNITED STATES PATENT OFFICE.

HENRY JUNG, OF BLOOMER, WISCONSIN.

FRUIT PROTECTOR.

Application filed June 10, 1921. Serial No. 476,439.

To all whom it may concern:

Be it known that HENRY JUNG, a citizen of the United States of America, residing at Bloomer, in the county of Chippewa and State of Wisconsin, has invented new and useful Improvements in Fruit Protectors, of which the following is a specification.

The object of the invention is to provide a device particularly for use by dealers in goods such as fruits, berries and the like, either fresh or packed which are attractive to flies and other insects and are subject to deterioration by exposure to the air as by becoming dried up, accumulating dust, etc., and yet which must be exposed to the view of the prospective purchaser in order that sales may be effected; and therefore more especially the object of the invention is to provide an interiorly visible but normally accessible receptacle suitable for arrangement over objects or aggregations of fruit, berries, grapes, dates, figs and similar articles from which the required quantities may be withdrawn from time to time by the salesman but which are not exposed to touch by the casual observer or customer or others unauthorized to handle the goods, said receptacle being of such a construction as to prevent a circulation of air coming in contact with the goods and prevent the access of insects, bugs, flies and the like and also prevent the settlement of dust upon the goods; and furthermore to provide a device of this type which may be fitted over the bottom of the box or receptacle in which goods like dates, figs, etc., are shipped to the dealer, merely upon removing the top and sides of the box without displacing the same from the bottom; and hence without disturbing the goods as originally arranged in the shipping case or receptacle; and with these objects in view the invention consists in a construction and combination of parts of which a preferred embodiment is shown in the accompanying drawings, wherein:

Figure 1 is a view in perspective of a display case embodying the invention.

Figure 2 is a vertical sectional view of the same applied over the bottom of a box in which goods such as dates have been shipped, the sides and top of the case or box having been removed.

The case consists of the side and end walls 10 and 11 consisting of an open frame of tin or like sheet metal forming corner standards

12, a bottom rim 13 and a top rim 14. The fillers of the walls serving to give an unobstructed view of the interior of the case are of glass or similar transparent material and the top and bottom of the case are open with the former fitted with a cover plate 15 of glass or like material having a marginal frame 16, hinged at one end as shown at 17 and provided at its free edge with a button 65 or grip 18.

The upper surface of the top rim 14 is fitted with a felt cushion 19 serving as a seat for the top or cover and not only as a packing to exclude air, dust and insects 70 but also as a means of relieving the jar of the cover in closing the same to minimize the risk of breakage, while the underside of the bottom rim 13 is provided with a cushion 20 of rubber or its equivalent to form an air tight contact with the surface of a counter, table or other flat support, around the edge of or upon the upper surface of a bottom 21 of a box in which goods such as dates, figs and the like have been shipped, and from which box the top and side walls have been removed to expose the contents as indicated in the drawing.

A receptacle or case such as described not only serves as a means of effectually protecting the goods housed and displayed therein under conditions complying with the requirements of sanitary regulations prescribed by boards of health and the like but gives the prospective purchaser an unobstructed view of the goods and hence a full opportunity to determine the character and grade thereof without permitting promiscuous handling or touching of the same, whereas the goods may be removed from the case in proper quantities for disposal by sale merely by raising the top or cover which is normally seated in air tight relation with the walls of the receptacle.

Having described the invention, what is claimed as new and useful is:

1. A protective show case for vegetable food products having transparent side and end walls, an open bottom, and an open top fitted with a movable lid or cover and adapted to be fitted over the bottom of a shipping box or case from which the top and side walls have been removed, said case having a skeleton frame of sheet metal comprising corner standards and top and bottom rims in which the edges of transparent fillers are seated.

2. A protective show case for vegetable food products having transparent side and end walls, an open bottom, and an open top fitted with a movable lid or cover and 5 adapted to be fitted over the bottom of a shipping box or case from which the top and side walls have been removed, the

upper and lower edges of said walls being provided with yielding cushions respectively for seating the lid or cover and for contact with a supporting surface.

In testimony whereof he affixes his signature.

HENRY JUNG.
